UNITED STATES PATENT OFFICE.

WILLIAM B. BLAKEMORE, OF SAN FRANCISCO, CALIFORNIA.

DESIGN FOR A CANDY.

Application filed June 30, 1924. Serial No. 10,015. Term of patent 3½ years.

To all whom it may concern:

Be it known that I, WILLIAM B. BLAKEMORE, a citizen of the United States, residing in the city and county of San Francisco, State of California, have invented a new, original, and ornamental Design for a Candy, of which the following is a specification, reference being made to the accompanying drawing, forming a part thereof.

Fig. 1 is a side elevation of a candy showing my new design.

Fig. 2 is a top plan view of Fig. 1.

I claim:

The ornamental design for a candy as shown.

WILLIAM B. BLAKEMORE.

Witness:

LINCOLN V. JOHNSON.
